ELECTRIC MAGAZINE WRENCH

Lewis A. Mooter, Stillwater, Okla.

Application October 20, 1934, Serial No. 749,290

4 Claims. (Cl. 81—125)

My invention relates generally to power driven wrenches, and particularly to an electrically driven wrench having a magazine for containing and dispensing nuts into position in the wrench to be turned onto the bolt or stud which is to receive one or more of the nuts, and an important object of my invention is to provide a device of the character indicated above which is simple and inexpensive, rugged and efficient, and easily manipulated.

Another important object of my invention is to provide a device of the character indicated above which enables greatly speeding up operations of placing and tightening nuts on the studs and bolts of machinery in the operations of assembling the same, especially in the assembling of automobiles on an automobile factory assembly line.

Other important objects and advantages of my invention will be apparent from a reading of the following description in connection with the drawings, wherein for purposes of illustration I have shown a preferred embodiment of my invention.

In the drawings:—

Figure 1 is a top plan view of the embodiment.

Figure 2 is an enlarged longitudinal vertical sectional view, taken through Figure 1 approximately on the line 2—2 and looking in the direction of the arrows.

Figure 3 is a transverse vertical sectional view taken through Figure 2 approximately on the line 3—3 and looking toward the right in the direction of the arrows.

Figure 4 is a side elevational view of the electric motor starting and stopping switch.

Figure 5 is an elevational view taken from the left of Figure 4 and showing the relation of one of the stops or actuating fingers to the switch arm which are on the bolt engaging rod of the wrench.

Referring in detail to the drawings, the numeral 5 generally designates the embodiment which comprises the casing 6 which is conveniently of cylindrical form and has an axial tubular extension 7.

A removable cover 8 closes the open end of the casing 6 and is spaced outwardly from a partition 9 centrally of which there is located a flange 10 which has an annular bearing groove 11 therein which forms the guide and bearing for the annular flange 12 which projects from the head 13 of the revoluble drum 14. The casing 6 has inwardly of the partition 9 a lubricant receiving neck 15 closed by a snap cover 16 in which is arranged a

tube 17 which has a part 18 feeding lubricant to the groove 11 for lubricating the contact of the drum flange 12 with the bearing flange 11.

The revoluble drum 14 has axially spaced from the head 13 the head 19 axially from which projects the elongated nut magazine tube 20 which has thereon longitudinally spaced flanges 21 and 22 which engage ball bearing structures 23 and 24 attached to the interior of the casing extension 7 so that not only the magazine tube 20 but the adjacent end of the drum is revolvably supported and prevented from moving longitudinally on their axes.

On the interior of the tubular extension 7 is an annular rib 25 opposed to an annular rib 26 on the exterior of the magazine tube 20; and an annular rib 27 is fixed to the interior of the casing extension 7 and opposed to an annular rib 28 fixed near the outer end thereof on the magazine tube 20. The described pairs of ribs act to position the packing members 29 and 30, respectively, which confine within the extension 7 between the packings a quantity of oil (not shown) which is introduced through the inlet 31 which is provided with the snap cover 32, whereby the ball bearing structures are kept adequately lubricated and power losses from friction and wear are reduced to a minimum in the operation of the wrench.

On the outer extremity of the magazine tube 20 is an annular boxing 32' which is of channel cross section and provided with an enlarged lip portion 33 which is provided with a groove 34 receiving an annular projection on the annulus 35.

Leaf springs 36 and 37 extend longitudinally in the boxing 32 to engage the cruciform nut retainers 38, 39 whereby the end nut 41 of the plurality of nuts 40 is prevented yieldably from moving outwardly of the outer end of the magazine tube under the pressure of the helical spring 42 which is interposed between the head of the drum 14 and a washer 43 engaging the last one of the nuts. The leaf springs 36 and 37 are adequately strong to hold the members 38 and 39 from turning and releasing the last nut 41.

Extending through the drum 14 and centrally through the nut magazine tube 20 and through the bores 44 of the nuts 40 is the longitudinally movable rod 45 which normally has a position slightly outwardly of the last nut 41 so as to engage the stud 46 ahead of the last nut 41 when the wrench is placed in relation to the stud to apply one or more of the nuts thereto. The inner end of the rod 45 is attached to a large helical coiled spring 48 which is interposed between the inner end of the rod 45 and the head 13 of the

drum 14. The rod has within the drum 14 a switch operating finger 47 and a switch operating finger 48 longitudinally spaced outwardly from the finger 47, both of these fingers being in position to engage the protuberances of the rotatable switch arm 49 of the start and stop switch 50. When the finger 47 engages the switch arm 49 the electric motor 51 is energized and through its pinion 52 engaged with the crown gear 53 on the left hand end of the drum 14 rotates the drum 14 and consequently the nut magazine tube 20, so as to rotate the nut 41 and the other nuts which come into its place, onto the stud or bolt 46, it being remembered that the left hand movement of the rod 45 necessary to apply the finger 47 operatively to the switch arm 49 is brought about by early contact of the right hand end of the rod 45 with the stud ahead of the nut 41. As the nut is threaded on the stud, the rod 45 will be pushed progressively toward the left until the finger 48 engages the switch arm 49 and throws the switch to an "off" position thereby deenergizing the motor 51. The switch and the fingers 47 and 48 are so arranged with respect to each other that the motor will be stopped immediately the nut has been threaded on the bolt or stud for the required distance, thereby saving unnecessary jarring of the motor and other mechanism of the wrench, as well as saving electric current, and enabling immediately withdrawing the wrench from the stud operated upon and transferring the same without adjustment to the next stud to receive a nut.

The motor 51 is conveniently mounted as indicated at 54 on the cover 8 of the casing 6 in which position its shaft 55 extends through the partition 9 so as to carry its pinion 52 in proper engagement with the crown gear 53. Connection with the switch 50 is made through contact rings 56 and 57 which are fixed to the interior of the casing 6 and engage corresponding contact rings 58 and 59 fixed to the exterior of the drum 14. A suitable conduit 60 leads from the contact rings 58 and 59 on the drum to the switch 50 while other conduits 61 and 62 lead from the contact rings 56 and 57 on the casing 6 to the motor 51 as indicated in Figure 2.

An annulus 63 mounted on the magazine tube 20 between the packing structure 29 and the annulus 21 is provided with a wiping ring 64 which prevents an undue quantity of the lubricant oil from moving in the left hand direction within the space between the tubular extension 7 and the nut magazine 20.

A suitable form of start and stop switch is illustrated in Figures 4 and 5, containing a base or support 65 on which is rockably mounted the rotatable switch arm 66 having long arms 67 and 68 and short arms 69 and 70. The long arms are adapted to engage the stationary contacts 71 and 72 which are mounted on the support so as to bridge these contacts and cause energization of the motor 51. Of course, when the short arms 69 and 70 are opposed to the contacts no electrical engagement takes place and the motor is deenergized. The shaft 73 has connected thereto the switch arm 49 which is engaged by the stops 47 and 48 on the control rod 45. Suitable webs 74 and 75 in the drum 14 support the switch 50 in place as indicated in Figure 2.

It is obvious that the magazine tube 20 and the nut handling structure connected therewith may be of any suitable shape to handle the particular type of nut to be operated with, such as hexagonal, or square, or elliptical or any suitable shape.

Although I have shown and described herein a

preferred embodiment of my invention, it is to be definitely understood that I do not desire to limit the application of the invention thereto, and any change or changes may be made in the materials, and in the structure and arrangement of the parts, within the spirit of the invention and the scope of the subjoined claims.

What is claimed is:—

1. A magazine nut wrench of the character described comprising a casing, a tubular nut magazine rotatably mounted in the casing and containing in axially aligned positions a plurality of nuts to be applied to receiving studs, motor means within the casing operatively engaged with said magazine for rotating the same for applying the nuts to the studs, switch means interposed between the motor and a source of electrical energy, and control rod means engageable with said switch means for starting and stopping the motor, said control rod being normally positioned in advance of the nut in the magazine to be first applied, the projecting part of the control rod being adapted to be first applied to the stud in advance of the first nut to be thereby moved to a position in which it closes the switch and energizes the motor, said rod being adapted to be positioned by completion of the threading of the nut on the stud so as to open said switch and deenergize the motor.

2. A magazine nut wrench of the character described comprising a casing, a tubular nut magazine rotatably mounted in the casing and containing in axially aligned positions a plurality of nuts to be applied to receiving studs, motor means within the casing operatively engaged with said magazine for rotating the same for applying the nuts to the studs, switch means interposed between the motor and a source of electrical energy, and control rod means engageable with said switch means for starting and stopping the motor, said control rod being normally positioned in advance of the nut in the magazine to be first applied, the projecting part of the control rod being adapted to be first applied to the stud in advance of the first nut to be thereby moved to a position in which it closes the switch and energizes the motor, said rod being adapted to be positioned by completion of the threading of the nut on the stud so as to open said switch and deenergize the motor, and spring means for holding the control rod normally in initial position in which it extends beyond the nut to be applied first.

3. A magazine nut wrench of the character described comprising a casing, a tubular nut magazine rotatably mounted in the casing and containing in axially aligned positions a plurality of nuts to be applied to receiving studs, motor means within the casing operatively engaged with said magazine for rotating the same for applying the nuts to the studs, switch means interposed between the motor and a source of electrical energy, and control rod means engageable with said switch means for starting and stopping the motor, said control rod being normally positioned in advance of the nut in the magazine to be first applied, the projecting part of the control rod being adapted to be first applied to the stud in advance of the first nut to be thereby moved to a position in which it closes the switch and energizes the motor, said rod being adapted to be positioned by completion of the threading of the nut on the stud so as to open said switch and deenergize the motor, and spring means for holding the control rod normally in initial position in which it extends beyond the nut to be applied first.

sition in which it extends beyond the nut to be applied first, and spring means in said magazine for moving the plurality of nuts along the magazine toward one end thereof.

- 5 4. A magazine nut wrench of the character described comprising a casing, a tubular nut magazine rotatably mounted in the casing and containing in axially aligned positions a plurality of nuts to be applied to receiving studs, motor 10 means within the casing operatively engaged with said magazine for rotating the same for applying the nuts to the studs, switch means interposed between the motor and a source of electrical energy, and control rod means engageable with 15 said switch means for starting and stopping the motor, said control rod being normally positioned in advance of the nut in the magazine to be first applied, the projecting part of the control rod being adapted to be first applied to the stud in advance of the first nut to be thereby moved to a position in which it closes the switch and energizes the motor, said rod being adapted to be positioned by completion of the threading of the nut on the stud so as to open said switch and deenergize the motor, and spring means for holding the control rod normally in initial position in which it extends beyond the nut to be applied first, and spring means in said magazine for moving the plurality of nuts along the 10 magazine toward one end thereof, and spring controlled means at the delivery end of the magazine for holding the nuts against the tension of the last-mentioned spring means and arranged to yield when the nut is pressed on the stud so as to release the nut being applied and to engage the next nut to retain the same.
